AMOS CUTTER, OF EAST BOSTON, MASSACHUSETTS.

Letters Patent No. 70,818, dated November 12, 1867.

IMPROVED SASH-SUPPORTER AND FASTENER.

The Schedule referred to in these Letters Patent and making part of the same.

TO ALL WHOM IT MAY CONCERN:

Be it known that I, AMOS CUTTER, of East Boston, in the county of Suffolk, and State of Massachusetts, have invented a new and improved Sash-Supporter and Fastener; and I do hereby declare that the following is a full, clear, and exact description thereof, which will enable others skilled in the art to make and use the same, reference being had to the accompanying drawings, forming part of this specification.

The present invention relates to a novel and simple constructed and arranged attachment for the sash or window-frame, which is such as to be susceptible of being brought to bear against the window or the sash-frame, as the case may be, with a greater or less amount of force, by a simple turning in or out of a thumb-screw, or other equivalent device.

In the accompanying plate of drawings my improved sash-supporter and fastener is illustrated, the figure being a front elevation of a window, showing a sash-frame arranged therein, and broken out to illustrate my improved constructed supporter.

A, in the drawings, represents the window-frame. B, the sash-frame, in and along the side rails or bars of which my improved supporter is arranged. My supporter consists of two curve-shaped arms D, each of which is hung upon a fulcrum, *a*, with a rubber roller or wheel, E, at one end; at the other engaged with an S-shaped holder, F, that, by means of a thumb-screw, G, is carried in and out when properly turned therefor.

By the rubber wheels the attachment is brought to bear against the window-frame, and with a greater or less degree or amount of pressure, according as the thumb-screw G is turned either in or out.

I claim as new, and desire to secure by Letters Patent—

The combination of the arms carrying the rollers or wheel-holder F, and thumb-screw G, or its equivalent, substantially as and for the purpose described.

The above specification of my invention signed by me this 20th day of June, 1867.
